HANDKERCHIEF

James Herbert Johnson, Washington, D. C., assignor to The Rochester Company, Inc., San Antonio, Tex.

Application January 19, 1934, Serial No. 707,426

1 Claim. (Cl. 132—78.5)

This invention relates to improvements in handkerchiefs and more especially to a novel handkerchief of the type designed to be carried by the hand for ornamental purposes.

5 The primary object of the invention is to provide a novelty handkerchief having a pocket connected thereto for the purpose of carrying a powder puff, compact or the like.

With the foregoing and other objects in view 10 which will appear as the description proceeds, the invention consists in the novel features herein-after described in detail, illustrated in the accompanying drawing and more particularly pointed out in the appended claim.

15 In the drawing:

Fig. 1 is a plan view of the improved handkerchief.

Fig. 2 is an elevation of the same in folded position and illustrating its appearance when suspended from a finger.

Fig. 3 is an enlarged vertical sectional view of a detail taken on the line 3—3 of Fig. 1.

Fig. 4 is an enlarged perspective view of a portion of the handkerchief.

25 Referring to the drawing, 5 designates a rectangular sheet of any suitable textile material forming the base or body of the handkerchief. A patch 6 has its lower edge 7 and its side edges 8 sewed to the sheet but the upper edge is left 30 unsecured so that the pocket 9 thus formed may be used for the reception of various articles. The patch may be of the same textile material as the sheet 5 or may be of a different textile material. In any event the pocket will be lined by lining patches 10 and 11 which will also be sewed to the sheet 5 along the lines 7 and 8.

35 Between the upper edges of the patches 6 and 11, a strip 12 is inserted between and sewed to these patches and this strip carries one half 13 of

a hookless fastener. A similar strip 14 is inserted between the upper edge of the patch 10 and the sheet 5 and is sewed in position, and this strip carries the other half 15 of the hookless fastener. 5

A closing member 16 for said fastener cooperates with the parts 13 and 15 and has a conventional handle 17.

A ribbon 18 or the like is sewed to one of the upper corners of the pocket to provide finger loops 10 19 through which a finger may be inserted for carrying the handkerchief.

It is obvious that the handkerchief and pocket may be made of any suitable textile fabric, but I prefer to make the same of crepe or chiffon. 15

From the foregoing, it is believed the invention may be readily understood and it is apparent that changes may be made in the exact details disclosed without departing from the spirit of the invention as expressed in the claim. 20

What I claim and desire to secure by Letters Patent is:

A novelty handkerchief comprising an imperforate sheet of flexible textile material, front, first and second patches of similar material secured to the sheet along their sides and bottom edges so as to form a pocket open at the top, a reinforcing strip extending along the upper edges of the front and first patches and secured to those patches, a portion of a hookless fastener secured 25 to the strip, another reinforcing strip extending along the upper edge of the second patch and said sheet and secured to the sheet and the second patch, another portion of a hookless fastener secured to the last mentioned strip, and a closing member 30 cooperating with said portions of the hookless fastener for closing the pocket. 35

JAMES HERBERT JOHNSON.
